UNITED STATES PATENT OFFICE

HORACE M. LITTLE AND EDGAR R. HOLMES, OF DENVER, COLORADO, ASSIGNEES TO
AMERICAN GYRO COMPANY, OF DENVER, COLORADO, A CORPORATION OF COLORADO

SPARK PLUG

Application filed March 11, 1932. Serial No. 598,184.

This invention relates to improvements in spark plugs of the type employed in connection with internal combustion engines.

It is the object of this invention to produce a spark plug of such construction that it will give two sparks within the combustion chamber and which will also be provided with a condenser element on which a charge is induced by the high potential current which has the effect of increasing the intensity of the sparks across the two spark gaps.

Another object of this invention is to produce a spark plug of such construction that it shall be provided with a detonating chamber located above the spark gaps and which will function to produce an explosion that will drive gas downwardly between the inner surface of the tubular metal body member and the outer surface of the insulating core so as to free the parts from carbon.

The above and other objects that may become apparent as this description proceeds are attained by means of a construction and an arrangement of parts that will now be described in detail, and for this purpose reference will be had to the accompanying drawing in which the preferred construction has been illustrated, and in which:

Fig. 1 is a longitudinal section through a spark plug constructed in accordance with this invention;

Fig. 2 is an end elevation of the same; and

Fig. 3 is a diagram showing the relationship of the two electrodes to the condenser element.

In the drawing reference numeral 5 indicates a tubular metal body member which is of the usual construction and is provided with a threaded section 6 that engages in the threaded spark plug openings of the engine. The inner surface of the opening in body member 5 is provided with an inclined shoulder 7 on which is supported a gasket 8. The insulating core 9 has a shoulder that rests on the gasket 8 and is also provided with another shoulder 10 on which a gasket 11 is supported. A clamping nut 12 is threadedly connected with the inside of the opening in the body member as indicated by reference numeral 13. The clamping member 12 holds

the insulating body member securely in place in a manner quite obvious from the drawing. The insulating member is provided with a downwardly extending portion 14 of somewhat smaller diameter than the corresponding portion of the opening in the body member. An electrode 15 extends through the insulating member from one end to the other and is attached at its upper end to the cylindrical member 16, whose outer surface is threaded as indicated by reference numeral 17. Member 16 has an outwardly extending shoulder 18 and an upwardly extending threaded portion 19. Secured to the upper end of the insulating member is a washer or ferrule 20 that is held in place by means of the flange 18. A cement plug 21 is provided below the lower end of member 15 and serves to hold the parts against accidental movement after they have been assembled. A threaded sleeve 22 is secured to the threaded plug 19 and serves as a terminal for the high tension wires.

The lower end of the body member is provided with two openings 23 in which are located the ends 24 of a U-shaped condenser element, whose base portion is indicated by reference numeral 25. The ends 24 are surrounded by a tube of dielectric material 26 and this is held in place by means of cement 27. The ends 24 of the U-shaped member being spaced from the inner surface of the opening by the dielectric 26 form a condenser by means of which a charge of electricity can be stored.

Referring now to Fig. 2, it will be seen that electrode 15 is spaced a short distance from the base 25 of the condenser member so as to form a spark gap 28. Another electrode which has been indicated by reference numeral 29 is secured in an opening 30 in the end of the tubular body member and is in electrical contact with the body member. The lower end of electrode 29 is bent at right angles so as to form a projecting portion 31 and is normally spaced a short distance from the condenser element so as to form a spark gap 32. By referring to Fig. 3 it will be seen that the condenser element is located between the two electrodes 15 and 31 and is separated

from each whereby spark gaps 28 and 32 are formed. When the spark plug is in place, it is connected by means of a conductor 33 to the secondary coil 34 of a transformer whose primary has been indicated by reference numeral 35. The other end of the secondary is grounded at 36 and the electrode 31 is also grounded through the engine in the usual manner. It is apparent from the inspection of Fig. 3, that when the electrodes 15 and 31 are subjected to a high potential difference, a charge will be induced on the condenser and this charge will contain a considerable quantity of electricity and when the potential difference becomes large enough to break down the two spark gaps, the condenser will be discharged, thereby producing a much more intense spark than if the condenser action were not present. Besides the condenser action, the action of the two spark gaps in series also has a tendency to produce a more intense spark than can be obtained by a single spark gap. The reason for the intensifying action of two spark gaps is not fully understood by the applicant, but it has been recognized and demonstrated by repeated experiments that this is a fact and applicant therefore takes advantage of this feature and combines with it the condenser element which forms the intermediate portion of the spark gap and thereby gets the accumulative effect of both of these intensifying actions.

Attention is called to the fact that that portion of the wall of the opening in the body member which has been indicated by reference numeral 37 is frusto-conical and that the corresponding portion of the outer surface of the insulating core, which has been indicated by reference numeral 38 is concave and therefore an annular chamber 39 is formed between the two surfaces. This chamber becomes filled with inflammable gas during the compression stroke and when the charge in the engine is ignited, the pressure within the chamber 39 increases very rapidly and by the time the flame reaches this gas, it is in condition to detonate, thereby producing a very strong explosion that drives the gas downwardly between the outer surface of the insulating core and the inner surface of the body member and tends to keep the walls free from soot and other accumulations.

From the above description it will be apparent that the spark plug shown and described is of a simple and substantial construction and so designed that there are two spark gaps in series which are both located within the combustion chamber of the engine and in addition to this the member 25 which extends between the two electrodes 15 and 31 is so connected with the body member that a condenser action results, the effect of which is to greatly increase the quantity of electricity discharge at each operation of the spark gap and therefore a much more intense

spark is produced than if a single spark were used or if two spark gaps were used without the addition of the condenser action.

Having described the invention what is claimed as new is:

A spark plug comprising, in combination, a tubular body member, an elongated core of insulating material extending through the same, an electrode extending through the core in the direction of its length and terminating beyond the inner end of the body member, the inner end of the body member having two substantially parallel spaced openings extending thereinto, a U-shaped condenser element having its ends extending into the openings, the ends of the condenser element being surrounded by dielectric material which serves to space them from the sides of the openings and to secure them to the body member, the condenser element being spaced a short distance from the electrode to form a spark gap, and an electrode electrically connected with the body member and spaced a short distance from the condenser element, whereby when the two electrodes are subjected to a difference of potential, the condenser element will receive an induced charge and whereby when the difference of potential between the two electrodes reaches a given value, the two spark gaps will be broken down and two sparks produced.

In testimony whereof we affix our signatures.

HORACE M. LITTLE.
EDGAR R. HOLMES.
